UNITED STATES PATENT OFFICE.

WILLIAM J. MEYER, OF MILWAUKEE, WISCONSIN.

SKEIN-HOLDER.

1,219,658.

Specification of Letters Patent. Patented Mar. 20, 1917.

Application filed August 19, 1916. Serial No. 115,776.

To all whom it may concern:

Be it known that I, WILLIAM J. MEYER, a citizen of the United States, residing at the city of Milwaukee, county of Milwaukee, 5 and State of Wisconsin, have invented new and useful Improvements in Skein-Holders, of which the following is a specification.

The object of my invention is, among other things, to provide a skein holder in 10 which the skein supporting arms and table clamping mechanism may be formed of wire, whereby such holder is comparatively cheap and simple in construction, while it is no less efficient than those holders of more expensive construction.

My invention is further explained by reference to the accompanying drawings, in which—

Figure 1 is a front view, and

20 Fig. 2 is a side view of my device, drawn at right angles to that shown in Fig. 1.

Like parts are referred to by the same reference numerals in both views.

1 represents a table of ordinary construction with which my skein holder is attached by the wire clamping mechanism comprising the upper clamping member 2, lower clamping member 3 and spiral coils 4, 4. The object of the spiral coils 4, 4 is to connect the members 2 and 3, while such members 2 and 3 are adapted to more rigidly engage the table 1. One end 5 of the clamping member 2 extends horizontally past said clamping member and is rigidly affixed to 35 the stationary hub 6, said member 5 being slightly tapered, whereby it is forced into an aperture formed in said hub, thereby holding said hub rigidly in place. The hub 6 is preferably provided at its outer end 40 with an annular collar 7 and near its opposite end with a disk 8, between which the cylindrical bearing 9 is formed for the reception of the coils 10, 10 of the arms 11, 11, and the arms 11 are provided with curved 45 loops 12 for the reception of the skein 13, and said arms are adapted to be brought together in a folded position, indicated by dotted lines 14, both when the same is packed and shipped and when placing the

skein 13 thereon. When the skein 13 has 50 been placed in the loops 12 said arms are brought at right angles to each other, as indicated in Fig. 1, whereby said skein is securely retained in place preparatory to winding the same.

The coils 10, 10 are loosely fitted to the hub 6, whereby the arms 11, 11 are free to revolve around said hub, while said coils serve to simultaneously support said arms from the hub between the bearings 7 and 8. 60 The disk 8 is securely retained on said hub 6 by friction or in any convenient manner, and it prevents said hub, when formed of wood, from splitting as the tapered end 5 of the wire 2 is driven therein.

Having thus described my invention what I claim as new and desire to secure by Letters Patent, is:—

1. In a device of the described class, the combination of a plurality of radial arms 70 formed of wire, provided at their outer ends with skein retaining loops, and at their inner ends with spiral coils adapted to loosely revolve upon a stationary hub, a pair of wire clamping members adapted to removably engage a horizontal member of a support, a hub attached to one of said clamping members, and means for retaining the inner ends of said radial arms in place on said hub.

2. In a device of the described class, the combination of a plurality of radial arms formed of wire, provided at their outer ends with skein retaining loops, and at their inner ends with spiral coils adapted to loosely 85 revolve upon a stationary hub, a pair of wire clamping members adapted to removably engage a horizontal member of a support, a hub attached to one of said clamping members, and a pair of bearings secured to 90 said hub adapted to retain said radial arms in place thereon.

In testimony whereof I affix my signature in the presence of two witnesses.

WILLIAM J. MEYER.

Witnesses:

JAS. B. ERWIN,
ALICE J. MCKERIHAN.
